SUPPORT

William C. Holtzmann, New York, N. Y.

Application January 24, 1935, Serial No. 3,327

2 Claims. (Cl. 248—44)

This invention relates to aerial supports, clothes line supports, and similar devices, and has for its principal object the production of a simple and efficient means for facilitating the fastening of the support upon the wall of a building.

A further object of the invention is the production of a simple and efficient anchoring means for a support which may be used as an aerial, or dryer, and one of the important objects of the anchoring means is the provision of a clamp for firmly holding the anchoring means upon a wall or other supporting medium.

A still further object of this invention is the production of a simple and efficient standard for use in connection with the anchoring means or base.

A further object of the invention is the production of a simple and efficient means for anchoring the cross-arms upon a standard in an adjusted position.

Other objects and advantages of the present invention will appear throughout the following specification and claims.

In the drawings:—

Figure 1 is a perspective view of the improved support and anchoring means therefor, showing the support used as a dryer;

Figure 2 is a vertical sectional view through the structure shown in Figure 1, certain parts of the standard being shown in elevation;

Figure 3 is a perspective view of the anchoring base shown in Figure 1;

Figure 4 is a perspective view of a modified form of anchoring base;

Figure 5 is a perspective view of a further modified form of anchoring base;

Figure 6 is a perspective view of a still further modified form of anchoring base;

Figure 7 is a perspective view of another form of anchoring base;

Figure 8 is a perspective view of a modified form of support showing the same used as an aerial support;

Figure 9 is a front elevation of the upper end of the standard shown in Figure 8 showing the manner in which the cross-arm is secured thereto;

Figure 10 is a section taken on line 10—10 of Figure 9;

Figure 11 is a transverse sectional view through a modified form of connecting means between the cross-arm and the standard of the aerial support;

Figure 12 is a perspective view of the upper end of the aerial supporting standard;

Figure 13 is a fragmentary top plan view of the cross-arm carried by the aerial supporting standard showing the manner in which the aerial strands, or clothes lines may be attached to the cross-arm;

5

Figure 14 is a vertical sectional view through the standard illustrated in Figure 8;

Figure 15 is a top plan view partly broken away of the cross-arm shown in Figure 8;

Figure 16 is a perspective view illustrating a modified form of cross-arm provided with a hexagonal socket;

Figure 17 is a perspective view of the upper end of the lower section of a modified form of the standard;

15

Figure 18 is a perspective view of the upper end of the upper section of a modified form of the standard which may be used in connection with the present invention;

By referring to the drawings, it will be seen 20 that W indicates the wall or other support upon which the device is to be mounted. As shown in detail in Figure 3, I provide a base 20 which consists of a plate having a centrally raised portion 21 in which is provided an internally threaded 25 socket 22. This socket 22 is adapted to receive the lower end of the standard S and may be made sufficiently large to receive an externally threaded and internally threaded thimble 23 in the nature of an adapter, to accommodate various sizes of 30 standards. This base 20 is provided near two of its parallel side edges with track-ways 24 terminating short of the center of the base 20, as indicated at 25, and these track-ways 24 receive the adjustable clamping strips 26 which are slidably mounted within the track-ways 24. The clamping strips 26 are provided with downwardly bent substantially U-shaped clamping feet 27 which are preferably shaped to clamp about the upper ledge of the wall W, as shown clearly in 40 Figures 1 and 2. The inner end of each clamping strip 26 is provided with an upwardly extending ear 28. A clamping screw supporting lug 29 is carried by the base 20 upon either side and is anchored upon the base, as shown in Figure 3. A clamping screw 30 extends through the upwardly extending ears 28 of the clamping plates 26 and also through the lug 29, and this clamping screw 30 may be oppositely threaded at its ends which pass through the ears 28 for the 50 purpose of drawing the clamping strips 26 to a tightened position when the screw 30 is rotated in one direction and moving the clamping strips 26 to a loosened position when the clamping screw 30 is rotated in an opposite direction. This

55

screw may carry a removable key head 31 to facilitate the rotation of the clamping screw 30. As shown in Figure 3, the clamping plates or strips 26 mounted near opposite side edges of the base 20 are actuated in a similar manner as just described, the structure just described being duplicated on opposite sides of the base 20, as shown in Figure 3.

The standard S consists of a lower section 32 and an upper telescoping section 33. The lower section 32 is threaded into the adapter 23, and the upper section 33 is slidably mounted within the lower section 32 and is held in an adjusted position through the medium of a set screw 34. The upper end of the section 32 supports a cross-arm 35 which is held in an adjusted position through the medium of a set screw 36. This cross-arm 35 carries a plurality of hooks 36' which are connected to suitable rope connecting swivels 37 which connect the ropes or cables 38 to the cross-arm 35. Any desired number of these hooks and swivels may be employed without departing from the spirit of the invention.

The upper section 33 is provided with a reduced extension 39 upon which is fitted the upper cross-arm 40, this upper cross-arm 40 being anchored upon the upper section 33 in an adjusted position by means of a set screw 41. The upper cross-arm 40 also supports hooks 42 which engage rope securing swivels 43 to which the ropes 44 are attached.

In Figure 4 there is shown a modified form of the invention having a specially spaced base 45, which base 45 is provided with a flat central portion 46 and downwardly bent portions 47 near the side edges. Suitable clamping means 48 is carried by the base 45 constructed in a similar manner to that described and illustrated in Figure 3 for clamping this base 45 in position upon a wall which may be particularly shaped such for instance, as the type of wall illustrated in Figure 8.

In Figure 5 there is shown a further modified form of the invention wherein the base 49 consists of a relatively flat plate having a socket portion 50 arranged in the center thereof for supporting a standard. Track-ways 51 are carried by the upper face of the base 49, which track-ways receive clamping plates 52 having upwardly extending ears 53. An adjusting screw 54 is carried by one of the ears 53 and is threaded through the opposite ear for the purpose of facilitating the tightening of the plates 52 to a clamped position or moving the plates to a loosened position.

In Figure 6, there is shown another modified form of the invention illustrating a base 55 having a standard receiving socket 56 upon the upper face thereof. The base 55 is provided with upwardly extending apertured ears 57 near the corners thereof, through which apertured ears extends the threaded adjusting rod 58, this rod 58 being threaded and extending through the substantially U-shaped wall-engaging clamps 59, the adjusting rod 58 being so threaded as to draw these clamps together when the rod is rotated in one direction and spread the clamps apart when the rod is rotated in the opposite direction.

In Figure 7 there is illustrated a still further modified form of base 60 having a standard supporting socket 61 upon the upper face thereof. The base 60 is provided with elongated channels 62 near two of its opposite side edges and each channel is adapted to receive an elongated clamping rod 63, the rod 63 having threaded engagement with the clamp 64 in such a manner as to

cause the clamps 64 to be drawn together when the rod 63 is rotated in one direction and spread apart when the rod 63 is rotated in the opposite direction.

The present device is especially adapted for supporting clothes lines, aerials, and other similar means, the device as illustrated in Figure 1 being particularly adapted for supporting clothes lines and to be used as a dryer.

In Figure 8, however, the device illustrated is particularly adapted for use as an aerial support. In the structure shown in Figure 8, a wall will be noted, which is provided with a specially designed ledge portion B. The aerial support of the type illustrated comprises a base 70 carrying adjusting clamps 71, which clamps 71 are adapted to be drawn together so as to cause the ends 72 to fit in snug clamped engagement around the ledge B. The base 70 is provided with a standard supporting socket portion 73 upon which is mounted or fitted the lower section 74 of the standard. An upper adjustable section 75 is fitted within the lower section 74. This upper section 75 is provided with a reduced extension 76 which fits in a socket 77 formed in the cross-arm 78 and this cross-arm 78 is locked in position through the medium of a set screw 79. The cross-arm 78 is provided with a suitable connection 80 for securing the aerial wires 81 to the cross-arm 78. A lead-in wire 82 is secured to one of the wires 81 and passes through a guiding eye 83 near the top of the upper section 75 and through a guiding eye 84 near the bottom of the lower section 74 and down to a suitable inlet, the lead-in wire 82 being preferably guided through an eye 85 carried by the wall A.

In Figures 11, 12, and 13, there is shown a type of anchoring means for securing a cross-arm 86 to the standard 87. The standard 87 may be provided with a reduced extension 88 having a rib 89 extending longitudinally thereof for fitting in one of the radiating sockets 90 formed in the walls of the aperture 91 through which the reduced extension 88 is adapted to extend. This structure may provide an efficient means for holding the arm 86 at an adjusted angle relative to the transverse axis of the standard 87 to resist twisting movement of the arm upon the standard after it has once been placed in position. A suitable set screw 92 may be employed for holding the arm 86 against accidental displacement from the standard 87. In connection with Figure 13 there is also shown a special type of socket used for securing the ropes or cables 94 to the cross-arms. This structure comprises a socket 95 which socket is provided with spaced arms 97 carrying an eye 98 which eye may be secured to a suitable hook 99 carried by the arm 86. The end of the rope 94 may be knotted, as at 100, for resisting the outward pull of the rope 60 within the socket 95.

Figures 16, 17 and 18 illustrate a different type connection between the cross-arm 101 and the standard 102. Figure 18 shows the upper end of an upper standard section 103, the upper and lower sections 103 and 102 being provided with hexagonal shanks 104 and 105 to fit in suitable hexagonal sockets of a type indicated by the numeral 106 upon the cross-arm 101. The assembled relation of these features will be found in Figure 14. A set screw 107 may be employed for holding the upper and lower sections 103 and 102 in adjusted position and a set screw 108 may be used for locking the arm 101 against longitudinal movement upon the standard. A suit-

able set screw 109 may be used for locking the upper cross-arm 110 in position.

It should be understood that certain detail changes in the mechanical construction, combination, and arrangement of parts may be employed without departing from the spirit of the invention so long as such changes fall within the scope of the appended claims.

Having described the invention, what I claim
10 as new is:—

1. A support of the character described including a base, apertured ears rising from said base and located near corners of the base with pairs of companion ears at opposite sides of the base, a threaded rod extending through each pair of companion ears with end portions of the rod projecting from the base, and substantially U-

shaped clamping members threaded upon the projecting end portions of each rod in a manner to move the clamping members towards and away from a clamping position as the rod is rotated.

2. A support of the character described includ- 5 ing a base, ears rising from the base adjacent opposite side edges thereof, threaded rods carried by said ears, and clamps having upstanding lugs formed with threaded openings receiving said rods to shift the clamps towards and away from 10 a clamping position when the rods are rotated, said clamps having depending portions located beyond margins of the base and terminating in inwardly extending claws at their lower ends for gripping a support when the clamps are moved 15 towards each other to a clamping position.

WILLIAM C. HOLTZMANN.
